CLAIM

The ornamental design for a cooking appliance, as shown and described.

DESCRIPTION

FIG. 1 is a front perspective view of a cooking appliance according to the design;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof; and,
FIG. 7 is a bottom plan view thereof.

(Continued)

The portions of the article shown in broken line form no part of the claimed design.

1 Claim, 6 Drawing Sheets

Related U.S. Application Data

continuation of application No. 29/695,608, filed on Jun. 20, 2019, now Pat. No. Des. 927,241.
